UNITED STATES PATENT OFFICE.

HENNING FRIEDRICH WALLMANN, OF CHICAGO, ILLINOIS, ASSIGNOR TO
THE WALLMANN ENGINE COMPANY, A CORPORATION OF ILLINOIS.

INTERNAL-COMBUSTION ENGINE.

SPECIFICATION forming part of Letters Patent No. 688,907, dated December 17, 1901.

Application filed December 11, 1899, Serial No. 739,962. (No model.)

To all whom it may concern:

Be it known that I, HENNING FRIEDRICH WALLMANN, a citizen of the United States, residing at Chicago, in the county of Cook 5 and State of Illinois, have invented certain new and useful Improvements in Internal-Combustion Engines, of which the following is a specification.

My invention relates to internal-combustion engines of the two-cycle type, in which a charge of compressed air is mixed in suitable proportions with an inflammable gas or oil vapor ignited and expanded within the combustion-cylinder and made to perform 10 work against the piston at every outstroke of the latter; and my present invention is in the nature of improvements upon the engine forming the subject-matter of my former application for Letters Patent, filed May 31, 1899, Serial No. 718,904. In said former application provision was made for permitting the idle backflow of fuel from the fuel-pump to the reservoir while the air-pump was scavenging the combustion-cylinder and causing 15 the components of each charge (air and fuel) to enter the combustion-cylinder at substantially the same pressure by effecting through mechanical means the simultaneous or substantially simultaneous closing of the exhaust-valve of the combustion-cylinder and the inlet-valve of the fuel-pump. My present improvements reside principally in the addition to the engine forming the subject-matter of my former application aforesaid of 20 a positively-operated valve for controlling the admission of fuel from the fuel-pump to the combustion-cylinder and of a peculiar quadruple-faced cam for determining the relative operations of the latter valve and the 25 inlet-valve of the fuel-pump and the exhaust-valve of the combustion-cylinder, all as hereinafter fully described and claimed.

My invention is illustrated in the accompanying drawings, in which—
45 Figure 1 is a view in central vertical section of my improved engine. Fig. 2 is a side view of the engine, showing the valve-actuating connections. Figs. 3 to 14, inclusive, are diagrammatic views illustrating various 50 positions of the valve-actuating mechanism at different points in the strokes of the pis-

tons; and Figs. 15 and 16 show an edge and an end view, respectively, of the valve-actuating cam.

Similar characters of reference refer to similar parts throughout the several views. 55

A designates the base or bed plate of the engine, in which is journaled the crank-shaft B, carrying a fly-wheel C.

Supported vertically on the bed-plate A is 60 a framework D, which supports at its upper end a combustion-cylinder E and an air-pump cylinder F. Arranged tandem with and forming an extension of the air-pump cylinder F is the cylinder G of the fuel-pump, 65 the plungers F' of the air-pump and G' of the fuel-pump being formed integral, as shown, or rigidly connected together, so as to move simultaneously under impulses imparted from the crank-shaft B through crank B² and 70 connecting-rod f. Within the combustion-cylinder E is the working piston or plunger E', the latter connected to and operating the crank-shaft B through the agency of connecting-rod e and crank B'. It will be noticed 75 that the two cranks B' and B² are not set in parallel relation to each other on the crank-shaft B, but about one-eighth of a revolution apart, the crank B', connected to the working piston E', being approximately forty-five 80 degrees in advance of the crank B², which actuates the pump-plungers F' and G'. The purpose of this relative arrangement of cranks will be disclosed later in the description of the operation of the engine. 85

Referring to the air-pump F, it will be noticed that the presence of the elongated plunger G', formed directly on the upper face of the air-pump plunger F', creates an annular air-compression chamber within the cylinder 90 F, to which air is admitted on the suction-stroke through the inlet-valve H, and out of which it is forced on the compression-stroke through a port I and a mixing device J, past valve K into the combustion-cylinder E. The 95 cylinder of the fuel-pump is provided, preferably at its upper end, with an inlet-valve L, normally held closed by a spring, but adapted to open on the suction-stroke and to be positively held open during the last portion of 100 the suction-stroke and at times during the first portion of the compression-stroke also

by means and for a purpose hereinafter described.

M designates the ordinary gas-reservoir or rubber bag from which fuel is supplied to the 5 pump G through a chamber m, containing a valve for the admission of air through pipe m', and, if desired, another chamber n, in which the gas and air may be more thoroughly mingled to form an incombustible mixture of fuel.

10 Referring now to the combustion-cylinder, K is its inlet-valve, and N designates its exhaust-valve. The latter is normally held to its seat by a spring, as shown; but it is positively opened at and during the proper period 15 in the engine's operation to effect the exhaust and scavenging of the combustion-cylinder by suitable mechanism, as hereinafter described.

The mechanism as thus far described is 20 substantially similar to that disclosed in my pending application, Serial No. 718,904, hereinabove referred to. I will now proceed to describe the improvements I have subsequently made upon the construction therein shown 25 and claimed and which comprise the gist of my present invention. In the aforesaid application I stated the desirability of having the components of each charge (compressed air and compressed fuel) enter the combustion-cylinder at equal or substantially equal pressures, and to that end in that application I provided means for permitting the idle backflow of a part of the fuel in the fuel-pump to the reservoir during the interval in 30 which the air-pump is engaged in scavenging the combustion-cylinder. I have since found, however, that in view of the fact that the air during the scavenging operation is under considerable pressure it is desirable to begin the 35 compression of fuel in the fuel-pump in advance of the completion of the scavenging operation, or, in other words, before the closing of the exhaust-valve of the combustion-cylinder, especially where a mixer, as J, is employed, so that the fuel may enter the latter cylinder under a slightly greater pressure than the air. To this end I provide in the 40 canal or passage-way connecting the fuel-pump with the combustion-cylinder, and in 45 addition to the regular automatic inlet-valve K of the latter cylinder, a positively-actuated controlling-valve O, which by means hereinafter described is opened at a predetermined interval after the closing of both 50 the inlet-valve of the fuel-pump and the exhaust-valve of the combustion-cylinder to admit the compressed fuel into the latter cylinder. The inlet-valve K of the combustion-cylinder has a hollow stem of considerable 55 length provided with a plurality of fine lateral ports near its lower end, as shown, and its casing K' is similarly ported near its lower end opposite the port I, so that the compressed fuel entering through the hollow valve-stem 60 and the compressed air entering through port I will be forced in opposite directions to meet each other in fine sprays through the lateral

ports in the valve-stem and its casing, respectively, and will enter the combustion-cylinder past the valve K in a thoroughly commingled state. Further detailed description of this mixing device is not here given, as it is not herein specifically claimed, but forms the subject-matter of a companion application.

75 Referring now to the mechanism for actuating and controlling the three valves L, N, and O, P P designate a pair of standards mounted on top of the cylinders E and F. In the upper ends of these standards is suitably journaled a horizontal rock-shaft Q. Rigidly secured on this rock-shaft are three short arms or tappets q, q', and q'', which at their outer ends engage the stems of the valves N, O, and L, respectively, at the right times to 80 effect the proper actuation of said valves, as hereinabove described. The rock-shaft Q is positively actuated from the crank-shaft B of the engine through the agency of a quadruple-faced governor-controlled cam-disk R on said 85 crank-shaft, said cam-disk engaging and actuating a roller r, journaled in one arm of a lever r', pivoted at r'' to the upper end of a standard a, the other arm of said lever being joined by an adjustable connecting-rod r''' to 90 a short arm r'', fast on the rock-shaft Q.

95 S indicates an igniter located in the upper or inner end of the combustion-cylinder. It may be of any known and approved type and construction and is not, therefore, shown and described in detail.

The operation of my improved engine will be best understood by reference to Figs. 3 to 14, inclusive, which illustrate diagrammatically the various positions of the pistons and valves and the operations taking place in the several cylinders at the commencement of and during the travel of the cam-roller over the four faces of the cam. The highest face (indicated by 4, Fig. 16) extends through 105 forty-five degrees, the next highest face (indicated by 3) extends through ninety degrees, the next to the lowest face (indicated by 2) also extends through ninety degrees, and the lowest face (indicated by 1) extends through 110 one hundred and thirty-five degrees. Referring now to Figs. 3, 4, and 5 and remembering that in practice the cam R is on the crank-shaft B and of course turns in the same direction as the crank-shaft, (see arrows,) it 115 will be observed that the cam-roller r has completed one-third of its travel (or forty-five degrees) over the lowest face 1 of the cam. At the instant the cam-roller under the action of spring r''' descended from face 3 to face 1 the 120 cranks were of course one-eighth of a turn back of their positions, as shown in Figs. 3, 4, and 5. At that instant the pump-pistons F' and G' were just half-way up on their compression-strokes and the engine-piston E' was 125 about five-sixths of the way up on its inward stroke. The inlet-valve L of the fuel-pump was of course closed, the air-pump had just completed its scavenging of the combustion-

cylinder, the exhaust-valve N of the latter cylinder had just closed, and immediately thereafter the fuel-controlling valve O had been opened and the air and fuel pumps F and G, respectively, had just begun to supply the components of the next charge through the mixer J to the combustion-cylinder E. At the positions of the pistons and valves shown in said Figs. 3, 4, and 5 the pump-pistons F' and G' have nearly finished their forcing strokes and the engine-piston E' has just completed its inward stroke, during the last portion of which (after the closing of exhaust-valve N) it was compressing the new charge. The fuel-controlling valve O is still open. Figs. 6, 7, and 8 illustrate the positions of the parts ninety degrees, or one-fourth of a turn, later than as shown in Figs. 3, 4, and 5. Here the cam-roller has just mounted from face 1 to face 2 of the cam. This has had no effect on valves L and N, but has allowed fuel-controlling valve O to close to its seat under the action of its controlling-spring. The pump-pistons F' and G' are about one-sixth of the way down on their suction-strokes, while the engine-piston E' is half-way down on its explosion or working stroke, the igniter S having fired the charge when the crank of the working piston had reached about forty-five degrees past its upper dead-center. It is here noted that the valve O is not timed to close at the very commencement of the suction-stroke of the pumps, for the reason that at that period in the operation the canal or passage-way (which is of considerable length) between the fuel-pump and combustion-cylinder is full of gas which it is desirable to draw back into the fuel-pump in order to prevent its being sucked down into the air-pump and swept out at the exhaust with the next scavenging blast, and thus wasted. The closing-spring of the fuel-inlet valve L is therefore made somewhat stiffer than the corresponding spring of air-inlet valve H. During about the first one-sixth of the suction-strokes of the pumps, therefore, the air-pump is drawing in air through its valve H; but the fuel-pump is drawing back fuel from said canal or passage-way. Now the closing of the valve O will be so timed as to just permit all the fuel in the canal to be drawn back into the fuel-pump, but to prevent air being drawn in after it from the air-pump through port I and the gas-canal. After valve O has been closed the valve L opens by suction and the fuel-pump begins to fill from the reservoir. During the next quarter-turn of the crank-shaft while the cam-roller is traveling over the face 2 of the cam, the valves L, N, and O remain in the positions shown in Figs. 6, 7, and 8. When, however, the cam-roller mounts the highest face 4 of the cam, as shown in Figs. 9, 10, and 11, the tappet q^2 is drawn down into engagement with the stem of the fuel-inlet valve L (previously opened by suction) and holds said valve open during the remainder of the suction-stroke of the fuel-pump piston, thus insuring the complete filling of the fuel-pump with fuel. The fuel-controlling valve O is still closed, and the exhaust-valve N of the combustion-cylinder has just been opened. The pistons of the air and fuel pumps are just finishing their suction-strokes, while the working piston E' has just completed its working stroke and the burned products of combustion have just commenced to exhaust past the open exhaust-valve N. For the next forty-five degrees travel of the crank-shaft the valves L, N, and O are stationary in the positions shown in Figs. 9, 10, and 11, during which time the pistons move from the positions shown in the latter figures to those illustrated in Figs. 12, 13, and 14. In that interval the pump-pistons F' and G' complete their suction-strokes, while the engine-piston E' makes about one-sixth of its upward or exhaust stroke, as shown in Figs. 12, 13, and 14. As now the cam-roller drops from face 4 to face 3 of the cam, tappet q^2 allows the fuel-inlet valve L to close, the fuel-controlling valve O is unaffected, while the exhaust-valve N is still held open, as shown. During the next quarter-turn of the crank-shaft, while the cam-roller is passing over the face 3 of the cam, the pistons will all advance upward and inward from their positions, as shown in Figs. 12, 13, and 14. Piston G' of the fuel-pump will be compressing fuel for the next charge, piston F' of the air-pump will be scavenging the combustion-cylinder, and piston E' of the combustion-cylinder will be expelling the products of combustion commingled with the scavenging-air. The valves L, N, and O will all remain in the positions shown in Figs. 12, 13, and 14. Finally, with the descent of the cam-roller from face 3 to face 1 of the cam, the exhaust-valve N will close, the fuel-controlling valve O will open, a fresh combustible charge will be forced through mixer J into the combustion-cylinder, and the hereinabove-described cycle of operations will be repeated.

In order to regulate and control the speed of the engine, the cam R, which is splined on the shaft B, is made capable of sliding thereon and longitudinally thereof and is connected to a centrifugal ball-governor T, located in the fly-wheel in the usual manner. The steps of the cam are formed obliquely across the periphery of the cam-disk instead of parallel with its axle, so that a longitudinal shifting of the cam-disk by the governor when the speed rises above normal causes all the valves to be actuated later in the engine's operation, with the result that a smaller combustible charge is fed to the combustion-cylinder and the speed of the engine is correspondingly decreased. The fuel-inlet valve L, it will be noticed, opens by suction; but the time of its closing is determined by the governor-controlled cam, and at times when its closing is delayed until after the fuel-pump piston G' has commenced its compression-stroke a part of the fuel will of course be

simply pressed back idly into the reservoir or rubber bag M.

Having thus described my invention, and illustrated the preferred embodiment thereof, 5 what I claim, and desire to secure by Letters Patent, is—

1. In an internal-combustion engine, the combination with the crank-shaft and the combustion-cylinder having its piston operatively connected to the crank-shaft, of air and fuel pumps connected to the crank-shaft 55 so as to be operated simultaneously therefrom, a canal or passage-way between the fuel-pump and the combustion-cylinder, a fuel-controlling valve in said canal, an automatic check-valve guarding the discharging 60 end of said canal, and valve-actuating mechanism operating to hold open said fuel-controlling valve until after the fuel-pump has begun its suction-stroke whereby the body of fuel remaining in said canal after each forcing stroke is drawn back into the fuel-pump, 65 substantially as described.
2. In an internal-combustion engine, the combination with the combustion-cylinder, of air and fuel pumps arranged tandem and 70 disposed parallel with said combustion-cylinder, a rock-shaft journaled transversely of the heads of said cylinders and carrying tappets adapted to engage and actuate the fuel-inlet valve, the fuel-discharge valve, and the 75 exhaust-valve of the combustion-cylinder, a single governor-controlled, multiple-faced cam on the crank-shaft, and connections intermediate said cam and the rock-shaft through which said cam controls and effects 80 the properly-timed movements of said valves, substantially as described.
3. In an internal-combustion engine, the combination with the crank-shaft and the combustion-cylinder having its piston operatively connected to the crank-shaft, of air and fuel pumps operated from the crank-shaft by a crank set at an acute angle to the crank of the combustion-cylinder, a canal or 85 passage-way between the fuel-pump and the combustion-cylinder, a positively-operated fuel-controlling valve in said canal, a duct connecting the air-pump with said canal adjacent the latter's entrance to the combustion-cylinder, and an automatic check-valve guarding the discharging end of said canal, substantially as described.
4. In an internal-combustion engine, the combination with the crank-shaft and the combustion-cylinder having its piston operatively connected to the crank-shaft, of air and fuel pumps operated from the crank-shaft by a crank set at an acute angle to the crank of the combustion-cylinder, a canal or 90 passage-way between the fuel-pump and the combustion-cylinder, a positively-operated fuel-controlling valve in said canal, a mixer located in said canal between the fuel-controlling valve and the combustion-cylinder, a duct connecting the air-pump with said canal through the mixer therein, and an automatic check-valve guarding the discharging end of 95 said canal, substantially as described.
4. In an internal-combustion engine, the

combination with the crank-shaft and the combustion-cylinder having its piston operatively connected to the crank-shaft, of air and fuel pumps connected to the crank-shaft 55 so as to be operated simultaneously therefrom, a canal or passage-way between the fuel-pump and the combustion-cylinder, a fuel-controlling valve in said canal, an automatic check-valve guarding the discharging 60 end of said canal, and valve-actuating mechanism operating to hold open said fuel-controlling valve until after the fuel-pump has begun its suction-stroke whereby the body of fuel remaining in said canal after each forcing stroke is drawn back into the fuel-pump, 65 substantially as described.

5. In an internal-combustion engine, the combination with the combustion-cylinder, of air and fuel pumps arranged tandem and 70 disposed parallel with said combustion-cylinder, a rock-shaft journaled transversely of the heads of said cylinders and carrying tappets adapted to engage and actuate the fuel-inlet valve, the fuel-discharge valve, and the 75 exhaust-valve of the combustion-cylinder, a single governor-controlled, multiple-faced cam on the crank-shaft, and connections intermediate said cam and the rock-shaft through which said cam controls and effects 80 the properly-timed movements of said valves, substantially as described.

6. In an internal-combustion engine, the combination with the combustion-cylinder, the air-pump and the fuel-pump, all connected to a common crank-shaft, of a fuel-controlling valve located intermediate the fuel-pump and combustion-cylinder, a multiple-faced cam on the crank-shaft, and mechanism operated by said cam and controlling and effecting the properly-timed movements of the fuel-inlet valve, the fuel-controlling valve, and the exhaust-valve of the combustion-cylinder, substantially as described.

In testimony that I claim the foregoing as 95 my invention I have hereto signed my name in the presence of two witnesses.

HENNING FRIEDRICH WALLMANN.
